UNITED STATES PATENT OFFICE.

WILLIAM S. GRAFTON, OF STEUBENVILLE, OHIO, AND EDWIN C. EWING AND ALEXANDER GLASS, OF WHEELING, WEST VIRGINIA, ASSIGNEES TO THE WHEELING CORRUGATING COMPANY, OF WHEELING, WEST VIRGINIA.

DESIGN FOR A CEILING-PLATE.

SPECIFICATION forming part of Design No. 22,274, dated March 7, 1893

Application filed February 4, 1893. Serial No. 461,220. Term of patent 14 years.

To all whom it may concern:

Be it known that we, WILLIAM S. GRAFTON, residing at Steubenville, in the county of Jefferson and State of Ohio, and EDWIN C. EWING and ALEXANDER GLASS, residing at Wheeling, in the county of Ohio and State of West Virginia, citizens of the United States, have invented and produced a new and original Design for Metallic Finishing-Plates for Buildings, of which the following is a specification, reference being had to the accompanying drawing, forming part hereof, which shows a metallic finishing-plate or ceiling-plate designed according to our invention. Our design consists of a square or rectangular finishing plate A, divided into equal parts or sub-divisions B, by ribs or projections a a', extending from one side of the plate to the other and crossing each other at right angles. The four angles of each sub-division are con-

nected by arc-shaped ribs d, of equal radius and equal length, and of which the four ribbed portions a a' of each sub-division form chords.

The essential feature of our design, is a metallic finishing plate sub-divided by 25 straight ribs or ridges crossing each other, and each sub-division having its angles connected by four arcs of equal radius.

We claim—

The design for a metallic finishing plate 30 herein shown and described.

In testimony whereof we have hereunto subscribed our names.

WILLIAM S. GRAFTON.
EDWIN C. EWING.
ALEXANDER GLASS.
